(57) **CLAIM**

The ornamental design for a leg massager, as shown and described.

DESCRIPTION

FIG. 1 is a front elevation view of a leg massager, showing my new design;

FIG. 2 is a rear elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The broken lines shown in the figures are for the purpose of illustrating portions of the leg massager, which form no part of the claimed design.
